SHARPENER FOR SHARPENING THE BLADES OF ICE SKATES AND LIKE ARTICLES

Robert L. Topping, Littleton, N.H., assignor to Norton
Company, Troy, N.Y., a corporation of Massachusetts

Filed June 7, 1966, Ser. No. 2,596

Term of patent 14 years

(Cl. D37—1)

Fig. 1.

Fig. 2.

Fig. 3.

FIGURE 1 is an end elevation view of a sharpener showing my new design;

FIGURE 2 is a side elevation view of the sharpener; and

FIGURE 3 is a top plan view of the sharpener.

I claim:

The ornamental design for a sharpener for sharpening the blades of ice skates and like articles, substantially as shown.
